UNITED STATES PATENT OFFICE

WESTERN UNDERWOOD, OF SANTA MONICA, CALIFORNIA

DESIGN FOR A STREET LAMP

Application filed August 25, 1930. Serial No. 36,753. Term of patent 3½ years.

To all whom it may concern:

Be it known that I, WESTERN UNDERWOOD, a citizen of the United States, residing at Santa Monica, in the county of Los Angeles and State of California, have invented a new, original, and ornamental Design for a Street Lamp, of which the following is a specification, reference being had to the accompanying drawing, forming a part thereof.

Figure 1 is a side elevation of the street lamp showing my new design, and Figure 2 a bottom elevation of the lamp.

I claim:

The ornamental design for a street lamp, as shown.

WESTERN UNDERWOOD.
